UNITED STATES PATENT OFFICE.

CHARLES P. MOSHER, OF PHILADELPHIA, PENNSYLVANIA, ASSIGNOR TO
THE ENTERPRISE MANUFACTURING COMPANY OF PENNSYLVANIA,
OF SAME PLACE.

DESIGN FOR A SAD-IRON HANDLE.

SPECIFICATION forming part of Design No. 33,656, dated December 4, 1900.

Application filed November 10, 1900. Serial No. 36,124. Term of patent 14 years.

To all whom it may concern:

Be it known that I, CHARLES P. MOSHER, a citizen of the United States, residing in Philadelphia, Pennsylvania, have invented and produced a certain new and original Design for a Sad-Iron Handle, of which the following is a specification.

My design for a sad-iron handle is fully illustrated in the accompanying drawing, which represents the handle in perspective.

The essential feature of the design is the ornamental side extension, as illustrated.

B is the base of the handle.

B' is the handhold, and projecting from one side of the handle is an ornamental extension

B². This ornamental extension has a circular portion b, connected to an arm b', projecting laterally from the base B, giving the effect clearly shown in the accompanying drawing.

I claim—

The design for a sad-iron handle as herein described and as illustrated in the accompanying drawing.

In testimony whereof I have signed my name to this specification in the presence of two subscribing witnesses.

CHARLES P. MOSHER.
